(57) **CLAIM**

The ornamental design for a glove with a segmented fingertip, as shown and described.

DESCRIPTION

FIG. 1 is a front perspective view of a glove with a segmented fingertip according to a first embodiment of my design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof;

FIG. 8 is a front perspective view of a glove with a segmented fingertip according to a second embodiment of my design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top view thereof; and,

FIG. 14 is a bottom view thereof.

The features shown in broken lines are environmental only and form no part of the claimed design.

Dash-dot lines adjacent un-shaded areas represent bounds of the claimed design and themselves form no part of the claimed design.

The areas of stipple fill presented in the second embodiment of the glove with a segmented fingertip illustrate a contrast in appearance.

A left-handed version of the glove with a segmented fingertip is shown in the Figures. Other embodiments are right-hand versions of the glove with a segmented fingertip that are mirror images of the first and second embodiments depicted in the Figures.
